US0D1075807S

(12) **United States Design Patent** (10) **Patent No.:** **US D1,075,807 S**
(45) **Date of Patent:** **** May 20, 2025**

(54) **DISPLAY SCREEN OR PORTION THEREOF
SHOWING A GRAPHICAL USER
INTERFACE**

(71) Applicant: **Apple Inc.**, Cupertino, CA (US)

(72) Inventor: **Lorena Pazmino**, San Francisco, CA (US)

(73) Assignee: **Apple Inc.**, Cupertino, CA (US)

(**) Term: **15 Years**

(21) Appl. No.: **29/893,859**

(22) Filed: **Jun. 2, 2023**

(51) LOC (15) Cl. **14-04**

(52) U.S. Cl.

USPC **D14/485**

(58) **Field of Classification Search**

USPC D14/485-495

See application file for complete search history.

(57) **CLAIM**

The ornamental design for a display screen or portion thereof showing a graphical user interface as shown and described.

DESCRIPTION

The sole FIGURE is a front view of a display screen or portion thereof showing a graphical user interface showing the claimed design.

The peripheral dashed broken lines illustrate a display screen or portion thereof, and form no part of the claimed design.

1 Claim, 1 Drawing Sheet
